J. A. B. SMITH.

TYPE WRITING MACHINE.

APPLICATION FILED DEC. 18, 1917. RENEWED OCT. 9, 1918.

1,304,213.

Patented May 20, 1919.

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,304,213.

Specification of Letters Patent. Patented May 20, 1919.

Application filed December 18, 1917, Serial No. 207,760. Renewed October 9, 1918. Serial No. 257,537.

To all whom it may concern:

Be it known that I, JESSE A. B. SMITH, a citizen of the United States, residing in Stamford, in the county of Fairfield and 5 State of Connecticut, have invented certain new and useful Improvements in Type-Writing Machines, of which the following is a specification.

This invention relates to the class of type-writing machine illustrated in the Wernery and Smith patent, No. 1,132,055, dated March 16, 1915, in which a fan-fold web is led around a cylindrical platen to be written upon, and in which the platen may be 10 displaced to permit the web to be straightened out, so that the carbon sheets, which are used to interleave the plies of the web, may be drawn backwardly relatively to the web; this being preparatory to typing a new form 15 or page on the web.

One of the principal objects of the present invention is to adapt a machine of this class for use with separate webs, loosely superposed, such webs being usually single ply. 25 One advantage of using separate superposed webs in place of a single fan-fold web is that the paper does not need to be of the same quality or color for all the plies. The outer 30 ply or web may be of high-grade paper, and may be elaborately or expensively printed, for receiving the ink-ribbon type impressions; while the remaining plies may be of thin paper, and simply or cheaply printed, suitable to retain for office copies or for 35 sending to branch offices.

The difficulty found in running separate superposed plies through a round platen typewriting machine is that the outer ply creeps ahead of the inner ply, owing to the 40 necessity of the loosely-assembled webs feeding at the same time around the cylindrical platen. This creeping is excessive where several plies, with their interleaved carbons, are fed through the machine; the result being 45 that eventually the outer ply is entirely out of register with the inner ply, so that the lines of typing, if correctly placed upon the outer ply, fall in incorrect positions upon the inner plies, especially the innermost.

According to the present improvements, the webs are provided with perforations, whereby the registration of the webs is renewed after the completion of the writing of 50 each of the successive forms thereon, so that

the errors, due to creeping of the outer webs, 55 cannot grow to an objectionable extent by accumulating from form to form. Upon the typewriting machine, at the delivery side of the platen, is carried a registration-renewing or re-alining device, comprising a set of pins 60 or gages to enter said perforations in the web, and thereby slip the webs slightly one upon another, or cam or jog them into proper relative register. This may be conveniently done after the platen has been displaced or shifted upwardly to straighten out the webs preparatory to drawing back the carbons between the webs; and after effecting the desired registration by means of these pins, they may be used to draw forwardly the webs, to gage them preparatory to typing the first line of the next form or page thereon.

When the work has thus been drawn forwardly and gaged by using the re-alining 75 pins, the platen may be depressed to normal position, and the form or section of the work which has been already typed may be cut off, and the severed section may be lifted off from the pins and removed from the machine; and the typing may then proceed upon the next form or section, which remains, of course, accurately gaged with reference to the printing point of the typewriting machine.

Other features and advantages will hereinafter appear.

In the accompanying drawings,

Figure 1 is a perspective view of an Underwood front-strike fan-fold typewriting machine, generally as shown in said Wernery and Smith patent, with the present improvements applied thereto.

Fig. 2 is a fragment of one of the webs, showing the re-alining perforations, which 95 are duplicated upon all the webs, whereby they may be newly registered with one another and with the printing point of the typewriter, preparatory to typing each fresh section or form of the web.

Fig. 3 is an enlarged perspective detail of a flap or device that may be used to press the sheets down upon the re-registering pins, and also to prevent them from falling off from the pins while the webs lie straightened out with their faces downward, as at Fig. 5.

Fig. 4 is a side elevation of a slide which

carries the pins, showing in section a few loose webs which have become relatively dislocated, and which are being placed upon the pins, first to bring them into relative 5 registration, and then to carry them to position for tearing off the written section and locating the first blank line on the succeeding section in position to receive the type impressions.

10 Fig. 5 is a sectional side elevation, illustrating the platen raised to permit straightening of the webs, and also showing the carbons drawn back and the webs advanced to position for tearing off one section or 15 form and proceeding with the typing of the next form.

There are illustrated in the drawings superposed webs 10, 11, 12, loose or separate one from another, each web consisting of a 20 single ply, although it is obvious that each may consist of two or more plies. These webs are interleaved by carbon sheets 13, and the assembled work (14) is led around a cylindrical platen 15. The diameter of 25 the curved path in which the outer web 12 of the work travels around the platen is greater than that of the path pursued by the inner web 10, so that the outer ply travels faster and creeps ahead of the inner ply; one of the objects of this invention being to prevent such creeping from accumulating to such an extent as to be objectionable.

It is for this purpose that each of the successive sections or forms 16, constituting each web, Fig. 2, is provided with perforations 17 forming a row across the web, so that the web presents these rows of perforations at intervals. The row of perforations 30 is preferably at the head of its form 16; and as a preparation for typing the first form upon the work, each web is impaled upon corresponding pins 18 mounted upon the typewriting machine. These pins may 35 have straight bodies of sufficient depth to accommodate a large number of webs, whereby the latter may be brought into exact registration with one another.

It will be understood that the webs may, 40 at any manipulation or feeding thereof, become a little out of register, as indicated diagrammatically at Fig. 4, and it will also be seen that the re-registering pins 18 are pointed, so as to have a camming effect upon 45 the sheets, to slip them into register with one another as they are pressed upon the pins. To facilitate this camming action, there may be as many pins 18 as desired, either two or more. The greater the number 50 of pins, the less work there is for each one to do upon the web, and hence less liability of any pin bending, crimping or tearing 55 the paper at the perforation.

To facilitate this camming operation in 60 registering or re-registering the sheets, there

may be provided a flap 19, which may be pivoted at 20, so that it may be swung down upon the sheets to pack them upon the pins; said flap preferably having forks or fingers 21 to pass between the pins 18, so as to be 70 effective in packing the paper against the plate or table 22 upon which the pins are erected. The flap, by means of a double-acting spring 23, may be held either in its open position, as at Figs. 1, 3 and 4, or in 75 its closed position, as at Fig. 5, in which position it prevents the inverted sheets from falling off from the pins 18.

By means of the same pins 18, the work is then advanced or pulled along to position 80 to begin the first line of typing; and the location of this first line may be determined by means of an adjustable gage 24, which is placed in the path of the part that carries the pins 18, said part being preferably in 85 the form of a slide or carrier 25, and being constructed to slide up along a supporting bar or track 26 at the delivery side of the platen, said gage being preferably mounted upon the same track above said slide for up- 90 and-down adjustment.

Therefore it will be seen that the leading sections of the webs 10, 11, 12, are first brought into register with one another by means of said pins 18, and then, while still 95 impaled upon the pins, are drawn forwardly thereby to exact writing position, determined by means of said gage 24.

The operator then returns the platen, platen frame, etc., to the normal positions, 100 seen at Fig. 1, and throws off the flap 19, as at Figs. 1, 3 and 4, and lifts the sheets from the pins 18, the pin-carrier 25 then sliding down to the Fig. 1 position. It will be understood that nothing is to be typed upon 105 the first form, that is, the form at the head of the web, which is now engaged by the pins. This first form is torn off by means of the usual knife 27, extending along the platen, and is thrown away, its usefulness 110 having ended after initially registering the webs and bringing them to position for writing the first line upon the second section. The carbons 13 may be originally inserted or located at said second section. 115

Said second section is now in position to receive the first line of typing, since the first blank line thereon is in register with the printing point of the typewriting machine.

The typing then proceeds, and the section 120 which was formerly the second (now the first) is filled out line by line, whereupon the operator swings the platen 15 up to the position at Fig. 5, in order to straighten out the webs, and pulls forwardly the webs and 125 (by means of the perforations) impales them all upon the pins 18. The latter are then in their rearmost positions, or nearest to the platen. The operator, by means of the usual handle 28, then throws back the 130

carriage 29, which carries the carbon sheets 13, to the proper station for co-acting with the next unwritten portion or form 16 of the work. Then the operator pulls forwardly, or away from the platen 15, the slide 25, which carries the pins, and thereby pulls forwardly all the webs as far as possible. The extent of this advance of the webs is determined (as before) by the gage 24, which is set at any desired point upon said track or bar 26, to be engaged by an abutting face of the slide 25, as at Fig. 5.

The operation of typing the web proceeds, the carbon carriage 29 advancing with the webs as they feed around the platen. As soon as the form is filled out, the operator again swings the platen up to the Fig. 5 position, impales the webs upon the pins 18 at the succeeding set of holes 17, throws back the carbon carriage 29, pulls forwardly the webs, restores the platen to its depressed position, tears off the form just typed, and proceeds with the writing of the succeeding form upon the web.

25 The leading portion of the webs may be guided by means of adjustable side-guides 30 placed upon the table 31, which usually inclines upwardly and rearwardly from the delivery side of the platen 15.

30 It will be understood that the webs may be supplied from separate spools or rolls, or otherwise.

One or more of the perforations 17 may all be used for binding the sections in loose-leaf binders. The strip or portion of the outer web 12, which contains the perforations 17, may, if desired, be severed from the remaining portion of the section, and, if desired, lines of perforations 32 may be provided adjacent to said holes upon said outer web for this purpose.

Variations may be resorted to within the scope of the invention, and portions of the improvements may be used without others.

45 Having thus described my invention, I claim:

1. In a typewriting machine, the combination with a revoluble platen and means for carrying carbons between superposed separate webs, said platen being displaceable to permit the straightening of the webs for relative readjustment between the webs and carbons, of a transverse row of registering pins at the delivery side of the platen, said 50 row extending longitudinally of the platen for re-registering the webs repeatedly by means of transverse rows of corresponding perforations repeated along the web at requisite intervals.

60 2. In a typewriting machine, the combination with a revoluble platen and means for carrying carbons between superposed separate webs, said platen being displaceable to permit the straightening of the webs for 65 relative readjustment between the webs and

carbons, of a web-registering device at the delivery side of the platen, said registering device movable to advance the webs.

3. In a typewriting machine, the combination with a revoluble platen and means for carrying carbons between superposed separate webs, said platen being displaceable to permit the straightening of the webs for relative readjustment between the webs and carbons, of a web-registering device at the 70 delivery side of the platen, and a severing device extending along the platen for severing sections from the webs, said registering device movable to advance the webs to position for severing.

4. In a typewriting machine, the combination with a revoluble platen and means for carrying carbons between superposed separate webs, said platen being displaceable to permit the straightening of the webs for relative readjustment between the webs and carbons, of a web-registering device at the 75 delivery side of the platen, said registering device movable to advance the webs, and a gage to determine the position to which said 80 registering device shall advance the webs.

5. In a typewriting machine, the combination with a revoluble platen and means for carrying carbons between superposed separate webs, said platen being displaceable to 95 permit the straightening of the webs for relative readjustment between the webs and carbons, of a web-registering device at the delivery side of the platen, said registering device movable to advance the webs, and a gage to determine the position to which said 100 registering device shall advance the webs; a track being provided for the movement of said registering device and the adjustment of said gage.

6. In a typewriting machine, the combination with a revoluble platen and means for carrying carbons between superposed separate webs, said platen being displaceable to permit the straightening of the webs for 110 relative readjustment between the webs and carbons, of web-advancing means engageable with the webs at the delivery side of the platen, and a support upon which said web-advancing means is movable.

7. In a typewriting machine, the combination with a revoluble platen and means for carrying carbons between superposed separate webs, said platen being displaceable to permit the straightening of the webs for 120 relative readjustment between the webs and carbons, of web-advancing means engageable with the webs at the delivery side of the platen, a support upon which said web-advancing means is movable, and means to 125 limit the extent of movement of said web-advancing means.

8. In a typewriting machine, the combination with a revoluble platen and means for carrying carbons between superposed sepa- 130

rate webs, said platen being displaceable to permit the straightening of the webs for relative readjustment between the webs and carbons, of web-advancing means engageable with the webs at the delivery side of the platen, a support upon which said web-advancing means is movable, means to limit the extent of movement of said web-advancing means, and web-severing means extending along the platen at the delivery side thereof, said limiting means and said web-severing means being relatively adjustable.

9. In a typewriting machine, the combination with a revoluble platen and means for carrying carbons between superposed separate webs, said platen being displaceable to permit the straightening of the webs for relative readjustment between the webs and carbons, of a set of registering pins at the 10 delivery side of the platen, said pins pointed so as to have a camming effect upon the sheets impaled thereon, thereby to re-register said sheets.

10. In a typewriting machine, the combination with a revoluble platen and means for carrying carbons between superposed separate webs, said platen being displaceable to permit the straightening of the webs for relative readjustment between the webs and carbons, of a clip to clip the webs at the 20 delivery side of the platen, and means supporting said clip for movement independently of the platen to advance the webs.

11. In a typewriting machine, the combination with a revoluble platen and means for carrying carbons between superposed separate webs, said platen being displaceable to permit the straightening of the webs for relative readjustment between the webs 30 and carbons, of pointed impaling pins at the delivery side of the platen to engage registering perforations in the webs, and a flap to press the webs down upon the pins.

12. In a typewriting machine, the combination with a revoluble platen and means for carrying carbons between superposed separate webs, said platen being displaceable to permit the straightening of the webs for relative readjustment between the webs 40 and carbons, of pointed impaling pins at the delivery side of the platen to engage registering perforations in the webs, and a flap to press the webs down upon the pins, said flap having fingers to pass between the pins.

13. In a typewriting machine, the combination with a revoluble platen and means for carrying carbons between superposed separate webs, said platen being displaceable to permit the straightening of the webs 50 for relative readjustment between the webs and carbons, of pointed impaling pins at the delivery side of the platen to engage registering perforations in the webs, a flap to press the webs down upon the pins, and

means for holding said flap in closed position. 65

14. In a typewriting machine, the combination with a revoluble platen and means for carrying carbons between superposed separate webs, said platen being displaceable to permit the straightening of the webs for relative readjustment between the webs and carbons, of pointed impaling pins at the 70 delivery side of the platen to engage registering perforations in the webs, a flap to press the webs down upon the pins, and means for holding said flap in either open or closed position.

15. In a typewriting machine, the combination with a revoluble platen and means for carrying carbons between superposed separate webs, said platen being displaceable to permit the straightening of the webs for relative readjustment between the webs and carbons, of means for mechanically 80 bringing said webs into re-registration with one another and advancing the webs to exact 85 writing position.

16. In a typewriting machine, the combination with a revoluble platen and means for carrying carbons between superposed separate webs, said platen being displaceable to permit the straightening of the webs for relative readjustment between the webs and carbons, of means for mechanically 90 bringing said webs into re-registration with one another and advancing the webs to exact 95 writing position, said means including a carrier and a set of registering pins thereon.

17. In a typewriting machine, the combination with a revoluble platen and means for carrying carbons between superposed separate webs, said platen being displaceable to permit the straightening of the webs for relative readjustment between the webs 100 and carbons, of means for mechanically bringing said webs into re-registration with one another and advancing the webs to exact 105 writing position, said means including a carrier and a set of registering pins thereon, 110 and also including a gage to which said carrier is movable together with the webs impaled on the pins.

18. In a typewriting machine, the combination with a revoluble platen and means for carrying carbons between superposed separate webs, said platen being displaceable to permit the straightening of the webs for relative readjustment between the webs and carbons, of means for mechanically bringing 115 said webs into re-registration with one another and advancing the webs to exact writing position, said means including a carrier and a set of registering pins thereon, and side-guides for the webs at the delivery side 120 of the platen.

19. In a typewriting machine, the combination with a revoluble platen and means

for carrying carbons between superposed separate webs, said platen being displaceable to permit the straightening of the webs for relative readjustment between the webs and carbons, of a web-registering device at the delivery side of the platen, said registering device movable to advance the webs, a paper table at the delivery side of the platen, and guides upon said table for the side edges of the webs.

20. In a typewriting machine, the combination with a revoluble platen and means for carrying carbons between superposed separate webs, said platen being displaceable to permit the straightening of the webs for relative readjustment between the webs and carbons, of a table at the delivery side of the platen, a set of impaling pins supported adjacent to said table, and side guides on said table for the leading portions of the webs.

21. In a typewriting machine, the combination with a revoluble platen and means for carrying carbons between superposed separate webs, said platen being displaceable to permit the straightening of the webs for relative readjustment between the webs and carbons, of a table at the delivery side of the platen, a set of impaling pins, a separate table upon which said impaling pins are mounted, said separate table forming a portion of a carrier, and means upon which the carrier is movable to advance the webs impaled upon the pins.

22. In a typewriting machine, the combination with a revoluble platen and means for carrying carbons between superposed separate webs, said platen being displaceable to permit the straightening of the webs for relative readjustment between the webs and carbons, of a table at the delivery side of the platen, a set of impaling pins, a separate table upon which said impaling pins are mounted, said separate table forming a portion of a carrier, means upon which the carrier is movable to advance the webs impaled upon the pins, and an adjustable gage to limit the throw of said carrier.

23. In a typewriting machine, the combination with a revoluble platen and means for carrying carbons between superposed separate webs, said platen being displaceable to permit the straightening of the webs for relative readjustment between the webs and

carbons, of a table at the delivery side of the platen, a set of impaling pins, a separate table upon which said impaling pins are mounted, said separate table forming a portion of a carrier, means upon which the carrier is movable to advance the webs impaled upon the pins, and a flap mounted upon said carrier for pressing the webs down upon the pins.

24. In a typewriting machine, the combination with a revoluble platen and means for carrying carbons between superposed separate webs, said platen being displaceable to permit straightening of the webs for relative readjustment between the webs and carbons, of a table at the delivery side of the platen, a web-severing device between the table and the printing point on the platen, and means, including a set of impaling pins, for registering the webs relatively to one another and to the printing point on the platen.

25. In a typewriting machine, the combination with a revoluble platen and means for carrying carbons between superposed separate webs, said platen being displaceable to permit straightening of the webs for relative readjustment between the webs and carbons, of a table at the delivery side of the platen, a web-severing device between the table and the printing point on the platen, and means, including a set of impaling pins, for registering the webs relatively to one another and to the printing point on the platen, said table being arranged between said pins and said severing device.

26. In a typewriting machine, the combination with a revoluble platen and means for carrying carbons between superposed separate webs, said platen being displaceable to permit straightening of the webs for relative readjustment between the webs and carbons, of a table at the delivery side of the platen, a web-severing device between the table and the printing point on the platen, and means, including a set of impaling pins, for registering the webs relatively to one another and concomitantly adjusting them to said severing device for severing the leading form or section from the web.
